DESIGN FOR A CASE FOR TAPE MEASURES

Eugene J. Witchger, Saginaw, Mich., assignor to
The Lufkin Rule Company, Saginaw, Mich.,
a corporation of Michigan

Application February 5, 1940, Serial No. 90,045

Term of patent 14 years

To all whom it may concern:

Be it known that I, Eugene J. Witchger, a citizen of the United States, residing at Saginaw, in the county of Saginaw and State of Michigan, have invented a new, original, and ornamental Design for a Case for Tape Measures, of which the following is a specification, reference being had to the accompanying drawing, forming part thereof.

Fig. 1 is a view showing the front face of a case for tape measures embodying my new design;

Fig. 2 is a similar view of the rear face; and

Fig. 3 is an enlarged sectional view, taken on the line 3—3 of Fig. 2.

I claim:

The ornamental design for a case for tape measures, as shown.
